Plastic Water Pipes In A Cut, Polypropylene Tube By: CanStock found on line Feb. 1, 2021 <https://www.canstockphoto.com/plastic-water-pipes-in-a-cut-48471215.html>.*Primary Examiner — Marissa J Cash*Assistant Examiner* — Rebecca Tsehay(74) *Attorney, Agent, or Firm* — Stinson LLP(57) **CLAIM**

The ornamental design for a vaporizer base, as shown and described.

DESCRIPTION

FIG. 1 is a perspective view of the vaporizer base; FIG. 2 is a top plan view of the vaporizer base of FIG. 1; FIG. 3 is a bottom plan view of the vaporizer base of FIG. 1;

FIG. 4 is a left side elevational view of the vaporizer base of FIG. 1;

FIG. 5 is a right side elevational view of the vaporizer base of FIG. 1;

FIG. 6 is a front elevational view of the vaporizer base of FIG. 1; and,

FIG. 7 is a rear elevational view of the vaporizer base of FIG. 1.

The broken lines in the drawings illustrate portions of the vaporizer base that form no part of the claimed design.
